[57] **CLAIM**

The ornamental design for a covered insulated canned beverage cooler, as shown and described.

DESCRIPTION

FIG. 1 is a front elevation view of a covered insulated canned beverage cooler showing my new design; FIG. 2 is a rear elevation view thereof; FIG. 3 is a left side elevation view thereof, the opposite side being identical; FIG. 4 is a top plan view thereof; FIG. 5 is a bottom plan view thereof; and, FIG. 6 is a cross-sectional view taken along line 6—6 of FIG. 3, the cover in an open position. The broken line showing of the can is for illustrative purposes only and forms no part of the claimed design.

FIG. 1

FIG. 2

FIG. 3

FIG. 4

FIG. 5

FIG. 6
